United States Patent

Des. 237,881
Patented Dec. 2, 1975

237,881

MINNOW NET

Rufus P. Steadman, 5726 Quince Road, Suite 16,
Memphis, Tenn. 38117

Filed May 1, 1974, Ser. No. 465,886

Term of patent 14 years

Int. Cl. D22—05

U.S. Cl. D22—22

FIG. 1

FIG. 2

FIG. 3

FIG. 5

FIG. 4

FIG. 1 is a perspective view of a minnow net showing my new design;

FIG. 2 is a front elevational view;

FIG. 3 is a side elevational view, the opposite side being the same;

FIG. 4 is a rear elevational view; and

FIG. 5 is a bottom plan view.

I claim:

The ornamental design for the minnow net, as shown and described.
